UNITED STATES PATENT OFFICE.

SPIROS C. MARKATOS, OF NEW YORK, N. Y.

COMBINED DRY ROOM AND IRON HEATER.

Application filed February 18, 1926. Serial No. 88,205.

This invention appertains to appliances for use in hat cleaning and blocking and like establishments and the primary object of the invention is to provide a novel combined hat drying chamber or room and a hot plate for sad irons and the like and novel means for associating said combined drying room and hot plate with a boiler, whereby a compact and convenient structure will be had and whereby the heat from the boiler can be utilized for the hot plate and drying room, the waste heat from the hot plate being also utilized in said drying room.

Another object of the invention is to provide novel means for combining said iron heater and drying room, whereby the irons to be heated can be conveniently placed on and removed from the hot plate and whereby the heat from the burner of the hot plate is permitted free access to the drying room without direct contact with the handles of the irons.

A further object of the invention is the provision of a novel combined hot plate and hat drying room attachment for hot water boilers adapted to be placed in superimposed relation and in close proximity to the hot water boiler, whereby the waste heat from the boiler can be effectively used for heating the hot plate and the drying room simultaneously, the burner for the hot plate being located relative to the boiler in such a manner that when the burner is in use, the heat therefrom will aid the heating of said boiler.

A further object of the invention is the provision of a novel heat collecting drum adapted to fit upon the upper end of a boiler with novel means for connecting a hot plate with the upper end of the drum and a drying room with the drum in superimposed position relative to the hot plate and in such a manner that a certain portion of the heat is allowed direct access from the drum into said drying room.

A further object of the invention is the provision of a novel heat deflecting flange carried by the hot plate for protecting the handles of the irons upon the hot plate from direct heat and for guiding the heat from the drum to the drying room.

It has heretobefore been contemplated by me, as shown in my prior Patent 1,493,361 issued to me May 6, 1924, for combining a hat drier with a boiler and for combining a hot plate with a boiler as shown in my prior Patent 1,497,730 issued to me June 17, 1924,

but it has heretobefore been impossible to incorporate both the iron holder and hat drying room with the upper end of the boiler.

It is therefore a still further object of this invention to provide the combined iron holder and hat drying room for boilers which is so constructed that these appliances will cooperate together in such a manner as to bring about a common end, namely the conservation of space and heat in a commercially successful article, which will be durable and efficient in use and which can be placed upon the market and dispensed to the trade at a small cost.

With these and other objects in view, the invention consists, in the novel construction, arrangement and formation of parts, as will be hereinafter more specifically described, claimed, and illustrated in the accompanying drawings, in which drawings:

Figure 1 is a side elevation of the improved combined hat drying room, hot plate and boiler,

Figure 2 is a vertical longitudinal sectional view through the combined hot plate and hat drying room in proper position relative to the boiler,

Figure 3 is a horizontal section taken on the line 3—3 of Figure 2 looking in the direction of the arrows, illustrating the formation of the novel hot plate and heat deflecting guides,

Figure 4 is a horizontal section taken on the line 4—4 of Figure 2 looking in the direction of the arrows illustrating the novel construction of the hat drying room and the rack for supporting the hats to be dried, and

Figure 5 is a detail perspective view of the novel combined hot plate and deflector.

Referring to the drawings in detail, wherein similar reference characters designate corresponding parts throughout the several views, the letter A generally indicates the improved device and B a boiler, with which the same is associated.

The boiler B is of the conventional type of hot water boiler usually heated by gas to generate steam and commonly used in the pressing, cleaning and blocking of hats and therefore will not be described in detail in the present application.

The improved device A comprises a drum 10, preferably of an annular shape, which is adapted to fit directly on the top of the boiler B and the lower edge of the drum can be beveled, as at 11 in order that a

snug fit may be had between the said drum and the boiler. The drum can be formed of sheet metal of the desired gage, or out of cast iron, and constructed in any other desired way, best suited for the purpose intended.

A collar 15 is seated within the upper end of the drum 10 and this collar is provided with an outwardly extending supporting 10 flange 16 which rests upon the top edge of the said drum. This collar forms a support for the hot plate 17, and the drying room 18, which will now be described. The hot plate 17 is preferably formed of cast iron 15 and the front and side edges thereof rest upon the flange 16 of the collar 15. The rear edge of the plate 17 is scribed on a different arc of a circle from the front edge thereof, so that the rear edge will be spaced 20 a predetermined distance from the flange 16 in order to provide a heat escape opening 19 for a purpose, which will be hereinafter more fully described. The rear edge of the hot plate 17 at the central portion thereof 25 is provided with a radially extending attaching lug 20 which can be bolted or otherwise secured as at 21 to the said flange.

The hat drying chamber or room 18 comprises a casing or shell 22 of substantially 30 cylindrical form and this shell has its front at the lower edge thereof cut away, as at 23, to permit convenient access to be had to said hot plate. The rear edge of the shell rests upon the flange 16 and this flange can 35 be provided with an arcuate vertically disposed supporting rib 24 to which the shell can be rigidly secured if desired. A deflecting plate of arcuate configuration, indicated by the reference character 25 is formed on 40 the rear edge of the hot plate 17 and extends into the casing or shell 22 directly in rear of the cut out portion 23 and this plate 25 serves as means for deflecting the heat from the opening 19 directly into the shell 45 and prevents the direct radiation of heat on the handles of the sad irons which may be placed upon the hot plate 17. It is to be noted, however, that the shell 22 is of such a diameter as to completely overlie the hot plate 17, so as to insure the proper use of 50 heat arising from the said hot plate. Directly above the cut out portion 23 of the shell, the same is provided with a door opening 26 which is adapted to be closed by a 55 suitable sliding door or closure 27 which is slidably mounted in upper and lower guide tracks 28 and 29. These guide tracks can be formed directly on the shell or attached thereto in any desired way. A manipulating 60 knob 30 can be secured to the door or closure 27 to facilitate the opening and closing thereof. As shown in the drawings, the shell is provided with a dome shaped top wall 31, but the same can be modified if 65 preferred.

Arranged within the dry room are suitable racks 32 for supporting the hat to be dried and as shown, each one of these racks embody straight rods 33 and 34 and an outwardly bowed rod 35. These rods 33, 34 70 and 35 are attached to the opposite sides of the shell in any well known manner. By opening the door or closure 27, the hats can be readily placed on or removed from the said racks 32.

Arranged within the drum 10 and in relatively close proximity to the boiler is arranged any preferred type of gas burner 36, provided for heating the hot plate 17 and owing to the arrangement of the hot 80 plate, the drum 10 and the dry room, the heat from the burner can be also utilized for said dry room.

In use of the improved device, the arrangement is such that a compact structure 85 is had, whereby the space will be conserved as well as the effective utilization of the heat. It is to be noted that the heat arising from the boiler will be collected in the drum 10 and consequently tend to heat the hot 90 plate and to flow through the opening 19 into the dry room. Further the heat arising from the burner 36 will heat the hot plate and also the dry room.

As clearly shown in the drawings, the 95 drum 10 is provided with a plurality of air inlet openings 12 in order to insure the proper functioning of the burner 36.

Changes in details may be made without departing from the spirit or the scope of 100 this invention, but:

What I claim as new is:

1. The combination with a heat collecting drum adapted to be arranged above a boiler, of a hot plate and drying chamber supported by said drum. 105
2. The combination with a heat collecting drum adapted to be arranged above and in axial alinement with a boiler and a burner in said drum, of a hot plate and drying chamber supported by and above said drum. 110
3. The combination with a heat collecting drum adapted to be resting upon the upper end of a boiler, of a hot plate supported by said drum, and a hat drying chamber supported by the drum and disposed directly above the hot plate. 115
4. The combination with an iron holder and a hat drying chamber adapted to be arranged directly above a boiler, of means for supporting the iron holder and hat drying chamber in predetermined position relative to the boiler. 120
5. The combination with an iron holder and a hat drying chamber, of a heat collecting drum supporting the iron holder and hat drying chamber adapted to be arranged directly above and in axial alinement with said boiler. 125
6. The combination with a drum, of the 130

boiler, a hot plate supported by and partially overlying the upper end of said drum defining in connection therewith a heat escape passage, and a hat drying chamber supported by the drum enclosing said hot plate and said heat escape passage.

7. The combination with a heat collecting drum, of an iron supporting plate supported by and partially covering said drum defining in connection therewith a heat escape passage, and a hat drying chamber supported by the drum and arranged directly above the hot plate and enclosing said heat escape passage, and a heat deflecting plate carried by the iron supporting plate in front of said escape passage.

8. The combination with a heat collecting drum, of an iron supporting plate carried by and partially covering the upper end of said drum defining in connection therewith a heat escape passage, a hat drying chamber supported by the drum and arranged directly above the hot plate enclosing said escape passage, the front end of the chamber having an opening therein at the lower edge thereof to permit access to be had to the hot plate at all times, and a heat deflecting flange carried by the hot plate and extending into the chamber at the front edge of said heat escape passage.

9. The combination with a heat collecting drum, of an iron supporting plate carried by and partially closing the upper end of the drum defining in connection therewith a heat escape passage, a burner arranged in said drum below the iron plate, and a hat drying chamber supported by the drum and arranged directly above the iron plate between said passage, the front of the chamber at the lower edge thereof being provided with an opening to permit access to be had to the plate at all times, a flange of arcuate configuration carried by said plate extending into the chamber at the front of said passageway, hat receiving racks arranged in the chamber, and a closure for said chamber to permit the placing and removing of hats from said racks.

10. As a new article of manufacture, a combined iron heater and hat drying chamber comprising a heat collecting drum, a burner in said drum, an iron supporting plate disposed upon the upper edge of the drum and partially closing the same defining in connection therewith escape passageways, a hat drying chamber supported by the drum and overlying said iron supporting plate, drying racks arranged in the chamber, a closure for the chamber to permit access to be had to said racks, the chamber having its lower edge thereof at one side cut away to permit ready access to be had to said iron supporting plate, and a heat deflecting flange formed upon the iron supporting plate in front of said passageway extending into the drying chamber.

11. As a new article of manufacture, a combined iron heater and hat drying chamber comprising a drum having air openings therein, a burner arranged in the drum, a collar fitted within the upper end of the drum having an outstanding flange resting upon the upper edge thereof, an iron supporting plate disposed on the flange and partially covering the upper end of the drum and defining in connection therewith a heat escape passageway, a supporting lug formed upon the plate engaging and secured to the flange at the rear end thereof, a shell resting upon said flange overlying the plate, a deflecting flange of arcuate shape carried by the plate in front of said passageway extending into the shell, in front of said heat escape passageway, and a closure for said shell.

12. In combination a hot water boiler, a hot plate supported in parallel spaced relation with the top of said boiler, a burner arranged between the hot plate and top of said boiler and a drying chamber rising from said hot plate and provided with an opening for allowing access to the top of said hot plate.

In testimony whereof I affix my signature.

SPIROS C. MARKATOS.
